UNITED STATES PATENT OFFICE

115,864

DESIGN FOR A BRUSH BACK OR SIMILAR ARTICLE

Norma S. Whiting, South Hadley, Mass., assignor to Pre-phy-lac-tic Brush Company, Northampton, Mass., a corporation of Delaware

Application February 2, 1939, Serial No. 82,745

Term of patent 3½ years

To all whom it may concern:

Be it known that I, Norma S. Whiting, a citizen of the United States of America and a resident of South Hadley, county of Hampshire, Commonwealth of Massachusetts, have invented a new, original, and ornamental Design for a Brush Back or Similar Article, of which the following is a specification, reference being had to the accompanying drawing, forming part thereof.

The figure is a rear perspective view of a brush back or similar article showing my new design.

The other side of the article shown is conventional. The characteristic features of my design reside in the surface ornamentation on the article shown.

I claim:

The ornamental design for a brush back or similar article, substantially as shown and described.

NORMA S. WHITING.
